ASSIGNORS TO FIRTH-STERLING STEEL COMPANY, OF MCKEESPORT, PENNSYLVANIA, A CORPORATION OF PENNSYLVANIA

APPARATUS FOR SHEARING FLANGES FROM INGOTS

Application filed August 20, 1929. Serial No. 387,135.

This invention relates to apparatus for shearing flanges from ingots.

In the copending application of L. Gerald Firth for ingot molds, Serial No. 385,255, filed August 12, 1929, there is disclosed a method of forming ingots having flanges thereon. The ingots are cast in ingot molds provided with recesses which form flanges on the ingot. After the ingots have been formed, the flanges are separated from the body of the ingots which contains the shrinks, pipes and segregations and the flanges are rolled or otherwise shaped to the desired form.

The present invention provides an apparatus for shearing the flanges from the body of the ingot.

In the drawings, which illustrate the present preferred embodiment of our invention,

Figure 1 is a partial vertical section showing a supporting die for an ingot having four flanges; and

Figure 2 is a similar view of the apparatus used for severing the flanges from an ingot having three flanges.

Referring more particularly to the drawings, there is shown a lower die 2, mounted on a base 3, and a pressing head 4 secured to a reciprocable plunger 5. The die 2 is provided with pockets 6 which receive the flanges 7 of the ingot A. The pockets 6 are larger than the ingot flanges 7 so as to provide clearance 8. In order to take care of any slight inequalities in the size of the flanges. The ingot is secured in the die 2 by a wedge 10 which is slidable relative to the die. The wedge is tapered and is moved relative to the die by a toggle lever not shown. When in the position illustrated in the drawings, the wedge contacts with one of the flanges 7 to rigidly hold the ingot in the die. The wedge 10 is provided with a dove-tailed portion 11 which slides in a corresponding groove in the die. The wedge is also provided with a flange 12 which contacts with one of the flanges 7 and prevents the ingot from turning during the severing operation.

The pressing head 4 has a knife 13 secured thereto by means of a bolt 14 and nut 15. A clearance pocket 16 is provided in the die to

receive the end of the knife. This clearance pocket 16 is formed in the surface 17, which supports the flange 7 which is being severed.

In the operation of severing the flanges from the ingot, the pressing head 4 and knife 13 are moved toward the ingot to force the knife entirely through the flange and to completely sever it from the body of the ingot.

The ingot is then rotated so that another flange 7 rests on the supporting surface 17 and the pressing head is again lowered to shear off the second flange. This operation is repeated until all of the flanges are removed. When severing the last flange it is necessary to insert a filling piece, not shown, between the ingot and the wedge 10.

In the embodiment shown in Figure 2, the ingot B has three flanges 7a. Corresponding parts in this figure are indicated by the same reference numerals with the letter *a* suffixed thereto. In the embodiment shown in Figure 2, the wedge 10a is of such shape that it holds the ingot B from being displaced from the die 2a. It is not necessary to provide the wedge 10a with a flange such as the flange 12 shown in Figure 1. The operation of severing the flanges is the same as described in connection with the embodiment shown in Figure 1.

We have illustrated and described the apparatus used for severing the flanges from ingots having three and four flanges. The invention is applicable irrespective of the number of flanges on the ingot. In the preferred forms of the apparatus illustrated in the drawings, the pressing head reciprocates in a vertical direction. If desired, however, the pressing head may move in a horizontal direction, as is common in the bull-dozer type apparatus. The pressing head may be of the pressing type or the hammer type.

Other changes may be made in the apparatus without departing from the spirit of the invention or the scope of the following claims:

We claim:

1. A device for shearing flanges from ingots having a body portion and flanges extending radially therefrom, comprising a supporting die provided with at least one pocket

- adapted to receive one flange of the ingot and a supporting surface for a second flange, the die pocket providing clearance for the ingot flanges, a wedge slidable relative to the die for securing the ingot in the die, and a pressing head and knife movable relative to the die, the cutting edge of said knife extending axially of the body of the ingot.
2. A device for shearing flanges from ingots having a body portion and flanges extending radially therefrom, comprising a supporting die provided with at least one pocket adapted to receive one flange of the ingot, and a supporting surface for a second flange, the die pocket providing clearance for the ingot flanges, a wedge slidable relative to the die and having a flange adapted to contact with a third flange of the ingot, and a pressing head and knife movable relative to the die, the cutting edge of said knife extending axially of the body of the ingot.

3. A device for shearing flanges from ingots having a body portion and flanges extending radially therefrom, comprising a supporting die provided with at least one pocket adapted to receive one flange of the ingot and a supporting surface for a second flange, the die pocket providing clearance for the ingot flanges, a wedge slidable relative to the die for securing the ingot in the die, and a pressing head and knife movable relative to the die, the die having a clearance pocket for the knife, the cutting edge of said knife extending axially of the body of the ingot.

In testimony whereof we have hereunto set our hands.

WILLIAM J. SCHULTZ.
ROBERT S. STEVICK.
